UNITED STATES PATENT OFFICE.

GEORGE J. BOHLMAN, OF MEDFORD, MASSACHUSETTS.

BOTTLE-LOCK.

1,279,077.

Specification of Letters Patent. Patented Sept. 17, 1918.

Application filed May 23, 1918. Serial No. 236,113.

To all whom it may concern:

Be it known that I, GEORGE J. BOHLMAN, a citizen of the United States, residing at Medford, in the county of Middlesex and 5 State of Massachusetts, have invented an Improvement in Bottle-Locks, of which the following is a specification.

My invention relates to a lock securing a bottle in an inverted position to a receptacle. 10 In connection with the vending of certain beverages, such as, for instance, mineral waters, orangeade, lemonade and the like, large glass bottles or carboys filled with the liquid are placed in an inverted position on top of a receptacle or cooler into which the liquid from the bottle flows until the liquid 15 in the cooler rises sufficiently to seal the mouth of the bottle. The receptacle or cooler is packed with ice to maintain a supply of chilled liquid from which the beverage 20 is drawn when desired.

It is common for the manufacturer of a beverage such as orangeade or a mineral water for instance, to furnish the cooler to 25 the retailer who dispenses the beverage and to replace the bottles of the liquid, as they become empty, with filled bottles.

The bottles or the cooler generally bear the name of the manufacturer or vender of 30 the particular beverage, or some trade mark by means of which his product may be distinguished from that of his competitors, and serves as a valuable advertising medium by which, by the excellent quality of the 35 product, its sale is promoted.

It is found that unscrupulous retailers or venders of the beverage, when the bottle is partially emptied remove the bottle from the cooler, add water or other diluent to the 40 contents until the bottle is again full and replace the filled bottle on the cooler and sell the diluted mixture for the original. The diluted mixture may have much the appearance of the original beverage, as it 45 shows in the bottle and by the distinctive marks on the bottle or cooler, the public is deceived into buying what they believe to be the product of a certain manufacturer, knowing from acquaintance with beverages 50 sold under such distinctive marks that they are in all respects satisfactory. The diluted or otherwise tampered with beverage has not the strength, or the other pleasing properties of the original and the reputation and 55 the business of the manufacturer are thereby injured, since the public, to a great extent,

ceases to buy beverages sold under his distinctive mark.

Consequently the object of my invention is in the provision of a lock whereby a bottle 60 or other container may be secured in inverted position on a receptacle against removal therefrom, until the lock is opened, which lock is so constructed that it may be operated only by one employing the proper 65 key.

The means whereby I accomplish the object of my invention is in the provision of two movable jaws, arranged in the receptacle and curved to substantially conform to the neck of the bottle, when in their most adjacent position. Said jaws are movable toward each other to substantially encircle the neck of the bottle to thereby prevent its removal from the receptacle. The 70 movement of said jaws into locking or unlocking relation with the bottle is controlled by a Yale or similar type of lock arranged in the outer surface of the receptacle, the turning of the proper key inserted therein 75 serves to move the jaws. By the provision of a lock of the Yale type, the lock is rendered practically immune from illegitimate operation and may be operated only by one who possesses the proper key. 85

Figure 1 is a sectional view of a receptacle or cooler embodying my invention and a bottle inverted thereon.

Fig. 2 is a plan sectional detail of Fig. 1, showing the lock in closed, or locking 90 position.

Fig. 3 is a plan detail showing the lock in open or unlocked position.

Fig. 4 is a detail of the jaw operating disk.

Fig. 5 is a sectional view along lines 5—5 of Fig. 3.

Fig. 6 is a detail of the outer wall of the receptacle or cooler, showing Yale lock.

As here shown the invention is applied to 100 a receptacle or cooler having an outer wall 10 and a top wall 11 adapted to support the bottle 12 in an inverted position on the cooler, said wall 11 having an opening 13 therein through which the neck 14 of the 105 bottle is adapted to be inserted.

A receptacle 15 for the liquid contained in the bottle is disposed within the outer wall 10 of the cooler, said receptacle is comparatively larger in diameter in relation to 110 its height to thereby form a storage space 16 for ice, between its top wall 17 which

has a comparatively large cooling surface, and the top of the cooler for the purpose of maintaining the contents of the receptacle 15 cold.

5 The receptacle 15 is formed with a neck 18 of comparatively large diameter, which extends above the opening of the bottle inverted in the cooler and in which the bottle locking means are arranged, said receptacle 10 is provided with a faucet 18' by means of which the chilled liquid in the receptacle may be withdrawn.

The means whereby the bottle 12 may be secured in position on the cooler includes 15 the lock 19 of the Yale type, fastened to the outer wall 10 of the cooler and which has a face 20 extending slightly therefrom. The lock is provided with a barrel portion 21 in the end of which is formed a key opening 20 22, whereby the barrel may be rotated by inserting the proper key in the opening and turning the key. Due to the construction of the lock, it is exceedingly difficult for the barrel to be rotated except by the proper 25 key.

A shaft or rod 23 is secured to and extended from the barrel portion 22 of the lock through the neck 18 of the receptacle 15 for engagement with the bottle locking means.

30 Said neck is provided with a packing gland 24 surrounding said shaft or rod to prevent leakage of liquid from the receptacle 15 into the space 16 adapted for the storage of ice.

35 The end of said shaft or rod extending within the neck 18 is provided with a disk 25 having cam slots 25' therein, by which the bottle locking means may be moved into or away from locking engagement with the 40 bottle.

The bottle locking means comprises essentially two flat jaws 26 which are supported by and slidably arranged between the walls 27 of the channel member 28.

45 Said channel member 28 is curved to conform to the shape of the neck 18 and is secured therein by means of the screws 29 and extends substantially entirely around the neck, being cut away adjacent the disk 50 25 to admit said disk within the neck.

Said jaws 26 are pivoted together and to the channel member 28 by means of the screw 30 whereby the jaws are secured within said channel member and permitted to be 55 moved toward or away from each other to lock or unlock the bottle in the cooler. The faces of the jaws adjacent the neck of the bottle are so shaped as to conform to the contour of the neck for substantially the entire circumference when said jaws are moved into locking position.

The channel member 28 is so positioned in the neck 18 of the receptacle 15 that when said jaws 26 are moved into locking engagement with the neck of the bottle, they en- 65

circle said neck above the enlarged mouth 31 thereof and thereby secure the bottle on the cooler.

Pins 32 are arranged in the ends 33 of said jaws 26 and are extended through the cam 70 slots 25' in the jaw operating disk 25 secured to the end of the shaft 23 extended from the lock and form means whereby the rotation of said shaft serves to move said jaws into or away from locking engagement 75 with said bottle.

Said cam slots 25' extend outwardly toward the periphery of said disk from points near the center of the disk and are so shaped or curved as to facilitate the movement of 80 the jaws upon a rotational movement of the disk.

When said disk 25 is in the position shown in Fig. 4 with the pins 32 therein at the inner part of the cam grooves near the center 85 of the disk, the jaws 26 are in their locking position surrounding the neck of the bottle and, due to the enlarged mouth 31 of the bottle, said bottle is thereby prevented from being removed from the cooler.

90 A rotational movement of said disk 25, caused by the turning of the key inserted in the opening in the barrel of the lock 19, causes the ends 33 of said jaws 26 to move outwardly, due to the cam grooves 25' and 95 the opening between said jaws is thereby increased sufficiently to permit the enlarged mouth 31 of the bottle to pass therethrough and the bottle to be removed from the cooler for replacement by a filled bottle. The turning of the key in the reverse, or locking, movement causes the disk to rotate to cause the ends 33 of the jaws 26 to approach each other and thereby encircle the neck of the 100 bottle to lock it in position on the cooler. 105

The locking means are so arranged, due to the Yale lock employed, that if a bottle is removed from the cooler and the jaws locked in closed position, they cannot be forced into open position to permit a bottle to be inserted in the cooler and it is necessary that the lock 19 be operated to cause the jaws to be moved.

110 It may be seen that the locking means comprises essentially two locks, one of which 115 serves to lock a bottle in the cooler and the other of which serves to govern the movement of the first lock.

I claim:

1. In a receptacle arranged to support a 120 liquid container in inverted position thereon, said container having a neck adapted to extend within said receptacle, of means arranged to encircle said neck to lock the container to said receptacle.

125 2. In a receptacle having an outer wall and an inner liquid receiving compartment, and arranged to support a container in inverted position thereon, said container having a neck adapted to extend into said 130

liquid receiving compartment, of means arranged to engage the neck of said container to lock said container to said receptacle, and operating means for said locking means extended through the outer wall of said receptacle for operation from within said receptacle.

3. In a receptacle having an outer wall and an inner liquid receiving compartment, 10 and arranged to support a liquid container in inverted position therein, said container having a neck adapted to extend within said liquid receiving compartment, of locking means arranged to engage said neck to lock said container to said receptacle, and a lock governing said locking means arranged 15 in the outer wall of said receptacle.

4. In a receptacle arranged to support a container in inverted position thereon, said 20 container having a neck adapted to be extended within said receptacle, of locking means arranged to engage the neck of said container to lock said container to said receptacle and a lock to govern said locking 25 means.

5. In a receptacle arranged to support a container in inverted position thereon, said container having a neck adapted to be extended within said receptacle, of jaws arranged 30 within said receptacle and movable into engaging relation with the neck of said container to lock said container in inverted position on said receptacle.

6. In a receptacle arranged to support a 35 container in inverted position thereon, said container having a neck adapted to be extended within said receptacle, of jaws arranged within said receptacle and movable toward or away from engagement with the 40 neck of said container to lock said container to said receptacle, or unlock it in said container, and means to move said jaws into or away from locking relation with said container.

45 7. In a receptacle having an outer wall adapted to support a container in inverted

position thereon, and an inner liquid receiving compartment, said container having a neck adapted to extend into said compartments, of a pair of jaws supported by said 50 compartment and movable toward or away from locking relation with the neck of said container, an operating shaft extended from said jaws to the outer wall of said receptacle and means to move said jaws arranged 55 in said outer wall of said container.

8. In a receptacle having an outer wall adapted to support a container in inverted position thereon, and having an inner liquid receiving compartment, of jaws pivotally 60 arranged in said compartment and movable into or away from locking relation with the neck of said container to thereby lock said container in inverted position on said receptacle or permit it to be removed therefrom, a jaw operating member arranged in the outer wall of said receptacle, a shaft extended between said member and said jaws, and a disk having cam grooves thereon in engagement with the ends of said jaws, the 65 operation of said member serving to rotate said shaft to spread or close said jaws to unlock or lock the container on the receptacle.

9. In a receptacle arranged to support a 70 container in inverted position thereon, said container having a neck adapted to extend within said receptacle, of locking means arranged within said receptacle to engage said neck to lock the bottle to said container, 75 and a lock for said locking means in the outer surface of said receptacle, said locking means arranged to be operated by the turning of a key inserted in said lock.

In testimony whereof, I have signed my 80 name to this specification, in the presence of two subscribing witnesses.

GEORGE J. BOHLMAN.
